Primary Examiner—A. Hugo Word**Assistant Examiner—Doris Clark****Attorney, Agent, or Firm—W. Thad Adams, III****[57]****CLAIM**

The ornamental design of an extrusion for use in the
construction of a window, as shown and described.

DESCRIPTION

FIG. 1 is a perspective view of an extrusion for use in
the construction of a window showing my new design,
the center being broken away to indicate indeterminate
length; and,

FIG. 2 is an end elevational view thereof.

FIG. 1

FIG. 2
